[57] CLAIM

The ornamental design for a race car fishing lure, as shown and described.

DESCRIPTION

FIG. 1 is a top perspective view of a race car fishing lure showing our design;

FIG. 2 is a right side view thereof, the left side being a mirror image thereof;

FIG. 3 is a top view thereof;

FIG. 4 is a bottom view thereof;

FIG. 5 is a front view thereof; and,

FIG. 6 is a rear view thereof.

The broken line showing of hooks in FIGS. 1, 2, 5 and 6 is for illustrative purposes only and forms no part of the claimed design.
